(57) **CLAIM**

The ornamental design for a surveying handle, as shown and described.

DESCRIPTION

FIG. 1 is a front perspective view of a new design for a surveying handle.

FIG. 2 is a front perspective view of a new design for a surveying handle in a use orientation.

FIG. 3 is a front view of a new design for a surveying handle.

FIG. 4 is a rear view of a new design for a surveying handle.

FIG. 5 is a right side view of a new design for a surveying handle.

FIG. 6 is a left side view of a new design for a surveying handle.

FIG. 7 is a top view of a new design for a surveying handle; and,

FIG. 8 is a bottom view of a new design for a surveying handle.

The broken lines represent portions of the surveying handle that form no part of the claimed design.

1 Claim, 8 Drawing Sheets
